[57] **CLAIM**

The ornamental design for a wall partition layout tool, as shown and described.

DESCRIPTION

FIG. 1 is a front elevational view of a wall partition layout tool showing my new design;

FIG. 2 is a top plan view thereof;

FIG. 3 is a bottom plan view thereof;

FIG. 4 is rear elevational view thereof; and

FIG. 5 is a side elevational view thereof, the other side elevational view being a mirror image thereof.

FIG-2-

FIG-1-

FIG. 5.

FIG. 4.
